UNITED STATES PATENT OFFICE.

LAWRENCE R. COMSTOCK, OF ARDMORE, OKLAHOMA.

PLUMB-BOB.

1,110,897.

Specification of Letters Patent. Patented Sept. 15, 1914.

Application filed March 14, 1914. Serial No. 824,301.

To all whom it may concern:

Be it known that I, LAWRENCE R. COMSTOCK, a citizen of the United States, residing at Ardmore, in the county of Carter and State of Oklahoma, have invented new and useful Improvements in Plumb-Bobs, of which the following is a specification.

This invention relates to plumb bobs, the primary object being to provide a device of this character which is constructed in sections whereby the required size of plumb bob may be made up to meet the varying conditions of usage.

A further object is to provide a sectional plumb bob which is constructed of metal throughout and whose sections are adapted to be loaded with mercury and to be united by means of threaded connections, means being provided for protecting the threads of the different sections while not in use, whereby the device is rendered extremely durable and efficient for use by bricklayers, carpenters, or the like.

The invention consists in the features of construction, combination, and arrangement of parts, hereinafter fully described and claimed, reference being had to the accompanying drawings, in which:

Figure 1 is a side elevation of the device, showing the main body section employed; Fig. 2 is a longitudinal sectional view taken through the same; Fig. 3 is a side elevation of the device when the auxiliary body alone is employed; Fig. 4 is a longitudinal sectional view taken through Fig. 3; Fig. 5 is a side elevation of the device as extended by connecting the auxiliary body section with the main body section; Fig. 6 is a longitudinal sectional view through Fig. 5; Fig. 7 is a longitudinal sectional view through the main body section, when not in use, showing the closure plug for its threaded socket applied thereto; and, Fig. 8 is a similar view taken through the auxiliary section when not in use.

In the drawings, the numeral 1 designates the main body section of the plumb bob, which is constructed of some suitable metal to afford the necessary weight, and which is cylindrical in shape and hollow with its lower end closed. The lower end of the section 1 is provided with a conical point 2 which is preferably equal in length to the diameter of the body. This body section is provided in its upper end with a threaded

socket 3 for the reception of the reduced and partially threaded lower end portion 4 of an auxiliary body section 5, when the said sections are united to provide an extremely long plumb bob, as shown particularly in Figs. 5 and 6 of the drawings. The said lower end of the section 5 is also provided with a conical point 6 which is adapted to fit within the socket 3 of the main body section, but which renders the auxiliary section adapted for use alone in forming a plumb bob of minimum length, as shown in Figs. 3 and 4. The body sections 1 and 5 are provided medially upon their outer peripheries with slightly enlarged, knurled portions 7 and 8, whereby both sections may be grasped effectively in the operation of connecting the same together as in Figs. 5 and 6, or in the act of detaching the same. A knurled suspension cap 9 to which the plumb line 10 is centrally attached is adapted to have its lower threaded end 11 engaged within the socket 3 of the body section 1 when a plumb bob of medium length is made up as shown particularly in Figs. 1 and 2 of the drawings. The threaded end of the said cap is adapted, however, to be fitted within a threaded socket 12 in the upper end of the auxiliary section 5, when this section alone is employed to afford a plumb bob of minimum length, or is coupled with section 1 to afford an extremely long device.

When the auxiliary body section alone is used in the composition of a plumb bob, it is necessary to protect the screw threads upon its lower end against injury, for the device is ordinarily subjected to rough usage. Therefore, a knurled protective sleeve 13, which is internally screw threaded, is adapted to be fitted onto the said lower end of the section 5 and is retained thereon when this section is not in use. Closure plugs 14 and 15 are also adapted to be threaded into the sockets 3 and 12 of the body sections 1 and 5 respectively to retain a load of mercury 16 in each section, whereby each section is rendered of maximum weight for its length.

From the foregoing description taken in connection with the accompanying drawings, it should be apparent to those skilled in the art to which this invention appertains that I have provided a simply constructed plumb bob which may be stored in

a small amount of space, when not in use, owing to its sectional construction, and whose sections may be employed to afford a plumb bob of the required size for each 5 operation.

What is claimed is:

1. A plumb bob comprising a plurality of cylindrical sections, each having its lower end pointed and being provided in its upper 10 end with a threaded socket, the lower end portion of one section being reduced and externally threaded for reception within the socket of the other section, and a line-attaching, suspension cap having a threaded 15 lower end adapted to be engaged within the socket of either body section.
2. A plumb bob comprising a plurality of cylindrical sections, each having its lower end pointed and being provided in its upper 20 end with a threaded socket, the lower end portion of one section being reduced and externally threaded for reception within the socket of the other section, a line-attaching, suspension cap having a threaded lower end 25 adapted to be engaged within the socket of

either body section, and an internally threaded protective sleeve adapted to be fitted onto the lower reduced end of the body section.

3. A plumb bob comprising a plurality of 30 hollow cylindrical sections, each having its lower end pointed and its upper end opened and threaded interiorly to provide a socket, the lower end portion of one section being reduced and externally threaded for re- 35 ception within the socket of the other section, a line-attaching, suspension cap having a threaded lower end adapted to be engaged within the socket of either body section, and a closure plug adapted to be 40 threaded into the socket of either body section, each section being adapted to receive a load of heavy substance.

In testimony whereof I affix my signature in presence of two witnesses.

LAWRENCE R. COMSTOCK.
